(57) **CLAIM**

The ornamental design of the vineyard post, as shown and described.

DESCRIPTION

FIG. 1 is a front elevational view of the vineyard post embodying the concepts of the present invention;

FIG. 2 is a fragmented top view of FIG. 1;

FIG. 3 is a fragmented left side elevational view of the vineyard post of FIG. 1;

FIG. 4 is a fragmented left side elevational view of the vineyard post of FIG. 1; and,

FIG. 5 is an enlarged perspective view of the portion labelled "5" in FIG. 2.

The dash-dot-dot broken lines of FIGS. 2 and 5 depict the limits of the enlarged view and form no part of the claimed design.

The drawings contain symbolic breaks. The portion between the break lines embraced by brackets forms no part of the claimed design.
